UNITED STATES PATENT OFFICE.

WILLIAM G. MATHIAS, OF ENSLEY, ALABAMA.

INGOT-MOLD.

1,290,627.

Specification of Letters Patent.

Patented Jan. 7, 1919.

Application filed March 24, 1917. Serial No. 157,098.

To all whom it may concern:

Be it known that I, WILLIAM G. MATHIAS, a citizen of the United States, and resident of Ensley, in the county of Jefferson and 5 State of Alabama, have invented certain new and useful Improvements in Ingot-Molds, of which the following is a specification.

My invention relates to the art of casting ingots and has particular reference to a 10 novel ingot mold.

It is well known that an economical production of steel requires the formation of ingots in which the pipes and segregated metaloids shall be located at a point near or 15 at the upper end in order that the amount of metal necessarily cropped shall be small. To this end many improvements have been suggested in methods of casting and in the form of the molds within which the ingots 20 are cast. Many of these recognize the necessity for quickly chilling the lower portion of the mold, causing the upper portion thereof to remain fluid for a longer time in order that fluid metal may be supplied to 25 compensate for shrinkage and to prevent the formation of pipes. In theory at least these improvements have resulted in the casting of better ingots, but many thereof entail such greater expense as to offset to a large extent 30 the advantages due to the saving in cropped metal.

Experience has shown that variations in speed of cooling in the lower half of the mold are unnecessary and undesirable; that 35 is to say, the lower portion of the ingot may freeze practically uniformly. It being understood, however, that the pipe usually forms at a point between the middle and upper end of the ingot, it is desirable that 40 means should be provided for retaining all that portion of the ingot thereabove in a fluid condition materially longer than the portion below that point. To this end I have provided means for uniformly cooling 45 all the lower portion of the ingot and for effectively insulating the upper portion thereof.

Furthermore, I have provided in a small-end-up mold a gradual taper in that portion 50 intended for quick cooling and a more decided taper in that portion intended for slow cooling, both tapers being in the same direction. By this means I am enabled to secure the desired results as to economical 55 production in a small-end-up ingot and in a one-piece mold. I am aware that ingots

having a double taper have been proposed for the purpose of insuring slow cooling at the top, but in none of the constructions of which I am aware is there found a mold having an integral hot top with tapers of different extent both in the same direction, the hot top portion providing for withdrawal of the metal from the surface of the mold in order to form an insulating air space.

I am aware also that certain forms of hot top linings have been proposed employing refractory material. An advantage accrues, however, in the employment of a hot top which is integral with the mold, utilizing 70 brick as the lining of refractory material. Brick may be selected which have a high refractory and insulating value and may be located in place and the mold used with less delay than if a plastic material were employed.

My invention will be more readily understood by reference to the accompanying drawings, wherein—

Figure 1 is a longitudinal vertical section 80 of a mold constructed in accordance with my invention, and

Fig. 2 is a plan view thereof.

In the drawings it will be seen that the mold 10 provides an internal cavity which 85 tapers upwardly and inwardly to the point 11. At this point the cavity is enlarged or counterbored, the counterbore itself being tapered upwardly and inwardly at a more acute angle than that of the lower portion. 90 While it is unimportant as to the shape of this counterbore, it is desirable that the same should be of the shape of the opening after the insulating material is located therein. This for the reason that I desire 95 to employ bricks 12 as the insulating material, and the shape of the opening must be such that a single course of bricks may be employed for filling the enlargement. After the bricks have been located, the cavity for the ingot has a gradual taper from the bottom to the beginning of the insulated portion, then a more acute taper to the top.

It will be noted that the walls of the 105 mold at the lower end are thinner than at the junction of the mold walls with the hot top. By this means I have determined that the cooling is substantially uniform. While the thicker walls induce more rapid cooling, yet the heat radiated from the thinner walls and rising along the sides of

the ingot tends to offset the more rapid cooling of the thicker walls and thereby produce uniformity.

By reason of the arrangement shown, an ingot may be formed in which the lower portion up to that point at which the pipe usually forms is cooled substantially uniformly while all that portion of the ingot above that point is retarded in cooling. In addition the advantage accrues of low operating and maintenance cost, due to the integral character of the hot top and the use of refractory brick instead of plastic refractory material.

I claim:

1. A mold for casting big-end-down ingots, comprising in combination walls defining an upwardly and inwardly tapering space, and an upwardly and inwardly tapering insulating lining for the upper end of the mold, the walls of the mold gradually increasing in thickness from the lower portion to the lined portion, substantially as described.
2. In a device of the class described, a mold having a cast metal body portion provided with an interior opening therethrough, the walls of said opening converging toward the top and the thickness of said walls gradually increasing from the lower portion toward the upper portion, the upper

portion being provided with a tapering counterbore greater in transverse dimension than the opening in said mold, and a lining of refractory material in said counterbore, said lining defining an opening which converges toward the top thereof, substantially as described. 35

3. In an ingot mold, the combination of walls of varying thickness, and an integral hot top, the walls increasing in thickness from the bottom toward the top and providing an upwardly converging mold cavity, the hot top having a replaceable refractory lining forming a continuation of said mold cavity, substantially as described. 40

4. In an ingot mold, the combination of walls increasing in thickness from the lower portion toward the upper portion providing an upwardly and inwardly tapering mold cavity, the taper being gradual to a point near the upper end, then more acute to the top of the mold, the more acute portion of the cavity being enlarged, and an inwardly and upwardly tapering insulation therefor, 50 substantially as described. 55

Signed at Ensley, Alabama, this 1st day of March, 1917.

WILLIAM G. MATHIAS.
